UNITED STATES PATENT OFFICE.

GUSTAF W. WINEBERG, OF BROOKLYN, NEW YORK.

DESIGN FOR A PICTURE-FRAME.

45,173.

Specification for Design.

Patented Jan. 20, 1914.

Application filed November 21, 1913. Serial No. 802,321. Term of patent 3½ years.

To all whom it may concern:

Be it known that I, GUSTAF W. WINEBERG, a citizen of the United States, residing at Brooklyn, in the county of Kings and State of New York, have invented a new, original, and ornamental Design for Picture-Frames, of which the following is a specification, reference being had to the accompanying drawing, forming part thereof.

The figure is a perspective view of a picture frame, showing my new design.

I claim:

The ornamental design for picture frame as shown.

GUSTAF W. WINEBERG.

Witnesses:

JOHN BRANDNER,
FRED. ROEGER.
